(57) CLAIM

The ornamental design for a vehicle floor mat, as shown and described.

DESCRIPTION

FIG. 1 is a perspective view of the vehicle floor mat showing our new design;

FIG. 2 is a top plan view thereof;

FIG. 3 is a bottom plan view thereof;

FIG. 4 is a left elevation view thereof;

FIG. 5 is a right elevation view thereof;

FIG. 6 is a front elevation view thereof;

FIG. 7 is a rear elevation view thereof;

FIG. 8 is a cross-sectional view taken along line 8-8 of FIG. 2;

FIG. 9 is a cross-sectional view taken along line 9-9 of FIG. 2; and,

FIG. 10 is a cross-sectional view taken along line 10-10 of FIG. 2.

The broken lines shown in FIGS. 1-10 are included to show portions of the vehicle floor mat that form no part of the claimed design.
